WILLIS J. BOYLE, SR., AND FRANK R. DALLMANN, OF LOS ANGELES, CALIFORNIA;
SAID DALLMANN ASSIGNOR TO SAID BOYLE.

CORRUGATING-MACHINE FOR CANS AND OTHER DEVICES.

1,365,887.

Specification of Letters Patent. Patented Jan. 18, 1921.

Application filed April 29, 1918. Serial No. 231,567.

To all whom it may concern:

Be it known that we, WILLIS J. BOYLE, Sr., and FRANK R. DALLMANN, both citizens of the United States, residing at Los Angeles, in the county of Los Angeles and State of California, have invented new and useful Improvements in Corrugating-Machines for Cans and other Devices, of which the following is a specification.

10 This invention relates to machines for corrugating cans and other containers and devices, and has for its object to provide an improved machine of the character mentioned which will be superior in relative simplicity and inexpensiveness of construction and organization, facility in use and control and in adaptation to varying conditions and classes of work and service, and which will be positive and speedy and accurate in 15 operation, and durable, and generally superior in efficiency and serviceability.

With the above and other objects in view, the invention consists in the novel and useful provision, formation, combination, assemblage, relative arrangement and association of parts, members and features, all as hereinafter described, shown in the drawings, and finally pointed out in claims.

In the drawings:

30 Figure 1 is a top plan view of a corrugating machine for cans and other devices, the same being constructed and organized in accordance with and to embody the invention;

Fig. 2 is an end view thereof looking in 35 the direction of the arrow appended to Fig. 1;

Fig. 3 is an end view of said machine looking in the direction opposite to that indicated by the arrow in Fig. 1;

40 Fig. 4 is a front elevation of the said machine;

Fig. 5 is a vertical transverse sectional view, taken upon the line x^5-x^5 , Fig. 4, and indicating a can in subjection to the action 45 of the machine to corrugate such can; such view being merely fragmentary to illustrate the working relations as between features of the machine and such can; and

Fig. 6 is a detail fragmentary vertical 50 sectional view, taken upon the line x^6-x^6 , Fig. 3.

Fig. 7 is a detail view showing the pin and slot connection between the levers which control the opening and closing of the divided bearing.

Corresponding parts in all the figures are designated by the same reference characters.

Referring with particularity to the drawings, the corrugating machine therein shown, comprises in the main, two co-acting working or corrugating members A and B, the former of which includes a shaft 7 and the latter of which includes a shaft 8, the upper of which shafts, 7, is suitably journaled at both ends, as at 9 and 10, in a machine frame 60 C, and the lower of which shafts, 8, is journaled at one end, as at 11, in the frame C, and the other end, as at 12, in a knock-down journal or bearing means e, which, when suitably manipulated, permits the opening 65 up or freeing of the respective end of the shaft for passage therefrom of the work or can which is to be brought into position between the corrugating members A and B so as to surround the corrugating member B, 70 75 as clearly shown in Fig. 5. The upper shaft 7 has its journal boxes 9 and 10 mounted to play vertically in suitable guides 11a in the frame C, and adjusting means D are provided for elevating or lowering such journal boxes 9 and 10 of the shaft 7, to relatively space the shaft 7 from the shaft 8, all in accordance with the working organization of the corrugating members A and B, as hereinafter delineated. To that end screw shafts 85 13 and 14 have thread connection with such boxes 9 and 10, as at 15, and such shafts at their upper end carry fixed miter gears 16 and 17 respectively, which respectively mesh with miter gears 18 and 19 upon a master shaft 20 journaled as at 21 and 22 at and extending lengthwise of the frame C. The shaft 20 carries a hand wheel 23 with a crank 24 whereby the shaft 20 may be revolved to operate the shafts 13 and 14 and 90 95 vertically adjust the boxes 9 and 10 with the shaft 7 of the upper corrugating member A.

E designates means for jointly driving the two corrugating member shafts 7 and 8 to revolve the same and cause them to co-act to corrugate the can disposed in part between them and passed on to the lower corrugating member B prior to the effective application to the shaft 8 of the knock-down bearing or journal means e. Such drive 100 means E may comprise a suitable train of gears, as disclosed, adapted to take power from any suitable prime mover or transmission means. The knock-down bearing means e comprise two separate angular lever mem- 110

bers or bell cranks, 25 and 26 respectively, which are respectively pivoted as at 25^a and 26^a in connection with the respective end of the frame C, and the shorter arms of which are loosely connected in overlapping relation as at 27, so as to be capable of pivotal movement in common. The longer arms of said lever members carry respectively journal members or bearing members 25^b and 26^b which are adapted to be brought together to jointly surround and form a complete bearing or journal for the shaft 8 as at 12; a pivotal latch member 28 being connected with the bearing member 26^b and adapted to 15 be brought into engagement with the bearing member 25^b tends to temporarily hold such bearing or journal members in assembled relation to revolvably sustain the otherwise free end of the shaft 8.

20 The lever member 25 is provided with a rigid handle member 29 whereby the two lever members may be jointly manipulated to bring them into assembled relation. A weight 30 loosely suspended from the point 25 of over-lapping loose connection at 27, of the lever member 25 with the lever member 26, exerts a constant tendency to disassemble the bearing members 25^b and 26^b and cause the same to swing apart upon their pivotal 30 supports at 25^a and 26^a.

The corrugating members comprise one or more corrugating die sections 31, which are generally circular in cross section, subject to modification in accordance with the design 35 of corrugation to be produced in the use and application of such die sections, and having their ribs extending parallel with the axis of rotation. These die sections are provided each with a central opening 32 where- 40 by the same may be passed upon the shaft 7 or the shaft 8, and such die sections are held in place by collars 33 similarly applied to the shafts, and the endmost of which, at corresponding ends of the shafts, are held 45 fixedly in place by pins 34. The die sections upon each shaft are held in assemblage at the other end of the shaft by a lock nut device 35 threaded on to the shaft. The collars 33 may be of any thickness, to be used 50 as blanks in mounting the die sections upon the shafts, so as to hold in aggroupment the proper number of die sections as shall be proportionate to the depth of can or 55 length of corrugating zone ranging endwise of the shaft; and such die sections may be of any suitable thickness and permit the outside dimension of a total assemblage of die sections properly proportioned, reckoning lengthwise of the shafts, to produce the desired corrugating effect upon the can or 60 other device.

Means F may be advantageously provided for effectively centering the can upon the lower corrugating member, as B, or preventing the same from lateral shifting and

opposing rocking or instability of the can or other device upon such lower corrugating member. Said means may comprise rollers 36 maintained in spaced relation and at opposite sides of the working zone of the machine, slightly beneath the horizontal plane of the lower shaft 8. These rollers may be supported each upon an adjustably opposed frame, there being two sets of such opposed frames, each frame comprising an upper member 37 and a lower member 38, loosely jointed together as at 39, and each provided with a collar 40, the upper collar surrounding a frame member 41 and the lower collar surrounding a frame member 42, lengthwise of which such collars may be adjusted and suitably fixed in positions of adjustment. Each upper frame member 37 carries one of the rollers 36. Thus there are four rollers, two on each side of the machine, for centering and stabilizing the can or other object, indicated at a in Fig. 5.

Stop means G may also be provided to limit the can or other device a from play of movement lengthwise of the corrugating member B, that is, in a direction the reverse of that of the arrow in Fig. 1. Such stop means may comprise opposite stop plates or members 42^a pivotally depending from the frame members upon which the upper collars 40 of the members F and G are mounted, each of such members 42^a being similarly provided with a collar 43, which collars surround said last mentioned frame members. These members may be suitably held in positions of adjustment endwise of the frame, so as to hold the can a or other device in proper position for suitable application and service of the corrugating members A and B.

The lower shaft 8 has a bearing 8^a at a point widely remote from the frame C, at the side opposite the journal means c, supported by brace arms 8^b so that the shaft 8 is firmly sustained in such bearing 8^a and the bearing 11, and sag at the free end of such shaft, namely, at the bearing c, is prevented.

The operation, method of use and advantages of the corrugating machine for cans and the like, constituting the invention, as exemplified by the form thereof herein disclosed, will be readily understood from the foregoing description, taken in connection with the accompanying drawings, and the following statement:

In order to emplace the can a or other device to be corrugated upon the lower corrugating member B, the knock-down bearing or journal c is thrown out of assemblage with the outer or free end of the shaft 8 by releasing the latch 28, whereupon the weight 30 causes the lever members 25 and 26 to swing so that the members 25^b and 26^b relatively separate and give free access to the end of the shaft 8. Thereupon the can may

be put in place, open end first, and brought against the suitably adjusted and positioned stop means G, and between the means F for centering and stabilizing the can or other device upon the lower corrugating member. This of course is all done while the upper corrugating member A is spaced from the lower corrugating member B, and after the can has been brought into position to be operated upon the hand wheel 23 is suitably rotated to rotate the screw shafts 13 and 14 and cause the boxes 9 and 10 to be lowered with the shaft 7, until the upper corrugating member A is brought to bear upon the can, in working relation to the lower corrugating member B. Just previously, the knock-down bearing c will have been re-organized by manipulating the handle member 29 to bring the bearing members 25^b and 26^b together, and latch the same by the locking device or latch 28, so that the free end of the shaft 8 and such knock-down bearing are assembled together operatively. Now, power may be applied through the means E for jointly operating the corrugating members, which latter will be revolved, producing the operative effect indicated in Fig. 5, and resultantly corrugating or fluting or creasing, or channeling, or distorting or otherwise affecting the wall or surface of the can or other device, all in accordance with the specific nature of the dies or sections 31, and in accordance with the nature of the work and the effect to be produced upon the same. The adjusting means D may now again be operated to elevate the screw shafts 13 and 14 with the boxes 9 and 10 and raise the upper shaft 7, so as to relatively separate the corrugating members (after application of power through the means E has been terminated), and the knock-down bearing or journal c may be disassembled by unlocking the same at the latch 28, whereupon such bearing members will swing apart and open up again the free end of the lower shaft 8. The can or other object may now be removed from the lower corrugating member and is in finished corrugated condition.

It is evident that by this machine a can or the like may be formed up completely without alteration of the component material, such as sheet metal, and after being brought into final can form or other form may then be corrugated and fixed, as it were, in its completed form by the strengthening or reinforcing incident to such corrugations or flutings. If the attempt be made to first corrugate the sheet metal or other material entering into the construction of the can, and then form the can, it will be necessary to operate in opposition to the obstructive and preventive influences of such strengthening or reinforcing corrugation or fluting. Manifestly the proper time to perform such fluting or corrugating is after the bending or

working of the can material into its final form. The form of the can may in this manner be most easily effected, and the resultant can may thus be stiffened into a non-yielding and reinforced and highly durable and stress-resisting unit. Also, as it is customary to build a rim wire or edge wire into various cans and containers, at the open mouth thereof, and this requires for accurate work a true cylindrical or other formation of the container mouth, it is much easier to accurately do this work when the container has been formed up of undistorted or uncorrugated, or unchanneled material, inasmuch as such corrugation or distortion of the stock tends to prevent such true formation of the container. In accordance with the present invention, the container is formed of uncorrugated material, and is formed into true and perfect shape, readily and truly receiving and being united with the rim ring or wire, prior to the corrugation of the completed container.

It is manifest that many changes and variations of the construction and inter-relation and mode of operation of parts, members and features, in distinction from the foregoing description and statement and drawings, may be made in adapting the invention to varying conditions of use and service, all without departing from the true spirit and essential attributes of the invention.

Having thus disclosed our invention, we claim and desire to secure by Letters Patent:

1. A machine for longitudinally fluting a tubular sheet metal body, including a frame provided with two sets of bearings and having a clearance opening at one end thereof through which the work is inserted in position and removed therefrom, one of the bearings being divided, a pair of substantially parallel shafts journaled in the bearings, complementary fluting rollers mounted upon the shafts and having the ribs thereof extending longitudinally of the shafts, and means for opening the divided bearing for the purpose of inserting the work in position or removing it therefrom, the work being moved in the direction of the ribs on the rollers.

2. In a machine of the character described, a frame provided with two sets of bearings, one of the bearings being divided, a pair of substantially parallel shafts journaled in the bearings, complementary fluting rollers applied to the shafts at points between the bearings, levers carrying the respective sections of the divided bearing, an operative connection between the levers for causing them to move in unison, and latch means for holding the divided bearing in a closed position.

3. In a machine of the character described, a frame provided with two sets of

- bearings, one of the bearings being divided, a pair of substantially parallel shafts journaled in the bearings, complementary fluting rollers applied to the shafts at points between the bearings, swinging arms carrying the respective sections of the divided bearing, latch means for holding the divided bearing in a closed position, means for causing the said arms to move in unison, and 5 means for automatically swinging the arms to open the bearing as soon as the latch means is released.
- 10

4. In a machine of the character described, a frame provided with two sets of 15 bearings, one of the bearings being divided, a pair of substantially parallel shafts journaled in the bearings, complementary fluting rollers applied to the shafts at points between the bearings, bell crank levers operatively connected to move in unison and carrying the respective sections of the divided bearing, and latch means for holding the divided bearings in a closed position.

5. In a machine of the character described, 20 a frame including end standards, a pair of substantially parallel shafts journaled upon the end standards and extending between

the same, complementary fluting rollers mounted upon the shafts between the bearings, rods connecting the end standards and arranged substantially parallel to the rollers, and stop members adjustably mounted upon the rods for engaging work to position the same properly upon the rollers.

6. In a machine of the character described, 30 a frame including end standards, a pair of parallel shafts extending between the end standards and journaled thereon, complementary fluting rollers applied to the shafts, rods connecting the end standards and arranged substantially parallel to the rollers, frame members extending between the rods and slidably mounted upon the rods for adjustment longitudinally of the rollers, and work positioning rollers carried by 35 the frame members.

40 In testimony whereof, we have signed our names to this specification in the presence of two subscribing witnesses.

WILLIS J. BOYLE, SR.
FRANK R. DALLMANN.
